Alan H. Norman

CLAIM

The ornamental design for a bottle, as shown and described.

DESCRIPTION

FIG. 1 is a first perspective view of a bottle showing our new design;

FIG. 2 is a second perspective view thereof;

FIG. 3 is a front view thereof;

FIG. 4 is a left side view thereof;

FIG. 5 is a right side view thereof;

FIG. 6 is a rear view thereof; and,

FIG. 7 is a bottom view thereof.

The broken lines in the drawing views represent unclaimed portions of a bottle, which are included for the purpose of illustrating unclaimed environment only, and forms no part of the claimed design.

1 Claim, 7 Drawing Sheets
